UNITED STATES PATENT OFFICE.

DAVY VANCE SICKMAN, OF DENVER, COLORADO.

HYDRAULIC CARTRIDGE.

1,141,077.

Specification of Letters Patent. Patented May 25, 1915.

Application filed April 13, 1914. Serial No. 831,418.

To all whom it may concern:

Be it known that I, DAVY VANCE SICKMAN, citizen of the United States, residing in the city and county of Denver and State 5 of Colorado, have invented certain new and useful Improvements in Hydraulic Cartridges, (Case A;) and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

My invention relates to improvements in hydraulic cartridges adapted for use in breaking down material in mines. Cartridges of this class are more especially 20 adapted for breaking down coal, after suitable preparation. For instance, a block or relatively large quantity of coal in bulk is prepared by forming a space for a considerable distance underneath the same, 25 after which a hole is bored above this block or mass, in which the hydraulic cartridge is placed. Water is then introduced to the cartridge under suitable pressure and acts upon the pistons within the shell or body of 30 the cartridge, whereby the latter are actuated and during such movement; act upon the body or block of coal to force or break the same downwardly. This has been found 35 the most advantageous manner of breaking down coal, since it avoids, as far as is possible, the production of slack or fine coal in work of this class.

My present improvement relates particularly to the special form of pistons employed 40 in cartridges of this character, together with the form of chambers in which these pistons are located. Heretofore, so far as I am aware, these pistons and chambers have been cylindrical in shape. This particular shape 45 of pistons and chambers is not exceedingly advantageous owing to the relatively small area of piston available, as compared with the size of the cartridge employed.

My improvement consists in forming the 50 pistons elongated, preferably ellipsoidal in shape, whereby the diameter of the piston, lengthwise of the cartridge, is greater than its diameter in the transverse direction. As illustrated in the drawing, these pistons are 55 shown both ellipsoidal and with rounded

ends and parallel opposite sides. Approximately the same results are obtained in both instances. The extremities of the pistons are grooved to receive tongues which are applied to the partitions between the chambers in which the pistons are located, these tongues being formed upon small plates which are readily removable. These plates also form stops to prevent the pistons from slipping entirely out of their chambers. 60 Provision is made, however, for exhausting the water from the chambers after the pistons have moved the desired distance, in order to properly perform the coal breaking function. This exhaust occurs before the 65 shoulders of the pistons reach the tongues of the stop plates, since the great pressure to which the pistons are subjected would cause the latter to shear or break the tongues engaging the counterpart grooves of the adjacent piston extremities. 70 75

Having briefly outlined my improved construction, I will proceed to describe the same in detail, reference being made to the accompanying drawing, in which is illustrated an 80 embodiment thereof.

In this drawing,—Figure 1 is a vertical longitudinal section taken through a hydraulic cartridge equipped with my improvement. Fig. 2 is a similar view, showing the pistons partially ejected. Fig. 3 is an underneath view or a view looking in the direction of arrow 3, Fig. 1. Fig. 4 is a cross section taken on the line 4—4, Fig. 1, looking toward the right. Fig. 5 is a section taken on the line 5—5, Fig. 2, looking 85 toward the right. Fig. 6 is a view similar to Fig. 3, showing a slightly modified form of piston. Fig. 7 is a vertical longitudinal section similar to Fig. 2, but illustrating a 90 modified form of construction, whereby the pistons are ejected successively from rear to front, instead of simultaneously, as illustrated in Fig. 2. 95

The same reference characters indicate the 100 same parts in all the views.

Referring first more especially to Figs. 1 to 3, inclusive, let the numeral 5 designate the body of the cartridge which consists of a cylindrical bar with chambers 6 formed 105 therein and open on one side to allow the pistons 7 to move out of the shell or bar in the performance of their function. These pistons are formed ellipsoidal in shape and the chambers 6 in which they are located are 110

of counterpart shape. To the top of each piston is applied a gasket or cup leather 8, the same being held in place by a plate 9 perforated to receive fastening screws 10 which are passed therethrough and threaded into the body of the piston. The pistons are grooved at opposite ends as shown at 12. These grooves are open at the exposed extremities of the pistons, shoulders or off-sets 13 being formed at the bottom of the grooves which are engaged by tongues 14 formed on stop plates 15 which are secured to the cartridge bar by fastening screws 16.

When the pistons are in their normal position within the bar 5, there is a space 17 above each piston for the introduction of water under the necessary pressure to eject the pistons for the purpose stated. This water is introduced through a relatively small duct or orifice 18 formed in a conduit 19 having one extremity 21 threaded into a recess formed in the extremity of the cartridge which is outermost when the device is inserted in the hole in the coal or other material which the cartridge is to be employed to break down. This orifice 18 registers with an orifice 20 of corresponding size formed in the adjacent end of the bar. From the upper extremity of the orifice 20 a relatively long orifice 22 extends through the upper part of the bar, its rear extremity terminating at a port 23 which communicates with the rearmost piston chamber. It should be explained that the terms "front" and "rear" or "forward and rearward" as employed in the description of these cartridges, has relation to their position when inserted in the hole formed in the coal, for instance, or other material where the cartridges are employed. Each of the other piston chambers is in communication with the duct or orifice 22 by means of a small port 23. By virtue of this construction the water which acts upon the pistons may be simultaneously introduced into all the chambers, whereby the pistons are approximately simultaneously ejected or forced downwardly into engagement with the coal for breaking down the latter.

As heretofore intimated, in Figs. 1 to 3, the pistons are technically ellipsoidal in shape. In Fig. 6, this form is slightly modified, since the extremities of the pistons are rounded or semi-circular, while their opposite sides between these extremities are straight, the opposite sides being parallel. This construction gives substantially the same results as are obtained by the ellipsoidal form. In other respects, the construction as disclosed in Fig. 6 is substantially identical with that shown in Fig. 3.

The form of construction shown in Fig. 7 is similar to that shown in Figs. 1 and 2, except that provision is made in the form 65 in Fig. 7 for successively ejecting the pis-

tons from the rearmost forwardly. In this construction, the liquid is introduced in the first instance, to the rearmost chamber, whereby the corresponding piston is partially ejected, after which a port or duct 70 in the partition separating the rearmost chamber from the next one forward, is uncovered, allowing the water to flow from the rearmost piston chamber to the adjacent chamber in front. In this event, the piston 75 in the last named chamber begins its outward movement and after it has moved the required distance, a corresponding duct or port formed in the partition separating the foremost chamber from the one next in the 80 rear is uncovered, after which the water enters the foremost chamber and the corresponding piston begins its outward travel. In this way, the pistons are progressively and successively actuated from the rear toward the front, the rearmost being first caused to act upon the coal and the other two in succession, whereby it is broken down by pressure acting thereon progressively forwardly. This method of operation 85 may be advantageously employed, as will be readily understood by those skilled in the art. In this form of construction (see Fig. 7), the water is first introduced to the cartridge through a duct 26 formed in a 90 conduit 27 and registering with a duct or orifice, 28, formed in the body of the cartridge and which leads rearwardly to a port 29, communicating with the rearmost piston chamber 6. After the piston has 95 been ejected some distance, a port 30 is uncovered, the same being formed in the partition 25, separating the rearmost chamber from that next in front. This port 30 communicates at its forward extremity with 100 the upper extremity of the piston chamber next in front. As soon as the water begins to enter the last named chamber, its corresponding piston begins to move outwardly and shortly uncovers a port 31 which places the central chamber 6 in communication with the foremost chamber, the rear extremity of the port 31 communicating with the upper extremity of the foremost chamber. In this way the pistons are progressively 105 ejected as heretofore explained, and the work of breaking down the coal most advantageously accomplished.

In the foregoing description, the use and operation of my improved hydraulic cartridge will be readily understood. The necessary water and the desired pressure may be supplied by any suitable apparatus, and the manner in which the hydraulic pressure acts upon the pistons of the cartridges will be readily understood from the explanation heretofore given. My improvement, as heretofore stated, consists in providing pistons, having relatively large areas 110 exposed to the hydraulic pressure delivered 115

120

125

130

to the cartridge, as compared with the diameter of the bar or shell of the cartridge in which the piston chambers are formed.

In order that the stop tongues 14 may be effective in limiting the outward movement of the pistons, provision must be made for the escape or exhaust of the water which acts to drive the pistons, as heretofore explained. Hence, the cartridge bar is provided near the outer extremities of the piston chambers with exhaust ports 32 through which the water begins to escape after the pistons have reached their predetermined outward travel for the purpose of breaking down the coal or other material, as heretofore explained.

Having thus described my invention, what I claim is,—

1. A hydraulic cartridge comprising a body member having elongated chambers formed therein and pistons of counterpart shape located in said chambers, the latter being open on one side of the cartridge, and means for introducing fluid to the cartridge for the ejection of the pistons.

2. A hydraulic cartridge comprising a body member having ellipsoidal chambers formed therein, pistons of counterpart shape located in said chambers, and means for introducing fluid to the chambers for the ejection of the pistons, the chambers of the latter being open for the purpose.

3. A cartridge of the class described, comprising a body member having chambers, pistons located in said chambers and means for introducing fluid to the chambers for the progressive ejection of the respective pistons.

4. A cartridge of the class described, comprising a body member having chambers, pistons in said chambers and means for introducing fluid to the said chambers for the ejection of the several pistons progressively from the rear toward the front.

5. A cartridge of the class described, comprising a body member having chambers and pistons located in said chambers, the body member having a duct extending from the front rearwardly, its rear extremity being in communication with the rearmost chamber, and ducts between the several chambers, which ducts are normally cut off from the fluid by the pistons, the said ducts in the partitions having their rear extremities below the tops of the pistons when the latter are in their normal or retracted position.

6. A cartridge of the class described, com-

prising a body member having chambers, pistons located in said chambers, the body member of the cartridge having a duct extending from the front rearwardly, its rear extremity being in communication with the rearmost chamber, ducts in the partitions between the several chambers which are normally cut off from the fluid by the pistons, the rear extremity of the duct next in front being nearer the top of its piston, when the pistons are in their normal or retarded position.

7. A cartridge having chambers formed therein, pistons in the said chambers, the extremities of the pistons being grooved, stop plates applied to the body of the cartridge and having tongues extending into the said grooves, the latter having shoulders at their inner extremities to limit the outward movement of the pistons, the chambers having exhaust ports to permit the escape of water from the chambers when the pistons have reached their predetermined limit of outward movement.

8. A hydraulic cartridge comprising a body member having an elongated chamber formed therein, and a piston of counterpart shape located in said chamber, the latter being open on one side of the cartridge, and means for gradually and continuously introducing fluid to the said chamber during the ejection of the piston.

9. A hydraulic cartridge comprising a body member having an elongated chamber formed therein, and a piston of counterpart shape located in said chamber, the latter being open on one side of the cartridge, and means for introducing fluid to the chamber for the ejection of the piston.

10. A hydraulic cartridge comprising a body member having elongated chambers formed therein, and pistons of counterpart shape located in said chamber, the latter being open on one side for each piston, and means for gradually and continuously introducing fluid under pressure to each piston chamber for and during the ejection of the piston.

In testimony whereof I affix my signature in presence of two witnesses.
